AUTOMATIC LATHE STOP SWITCH

Leon H. Height, Spring Lake, N. J.

Application March 6, 1941, Serial No. 382,069

1 Claim. (Cl. 200—47)

This invention relates to new and useful improvements in stop means for lathes and other machinery and more particularly to a switch adapted to be automatically operated by a moving part of the machine to be controlled, to the end, that the source of current to the power plant is cut off.

An important object of the invention is to provide an automatic machine switch which is positive acting in operation and not susceptible to the ready development of defects.

Another important object of the invention is to provide a switch of the character stated which can be readily adjusted to take effect under different operating conditions of the machine.

Still another important object of the invention is to provide a stop switch of the character stated wherein all of the parts are readily accessible for the purpose of repairs or replacement.

Other objects and advantages of the invention will become apparent to the reader of the following specification.

In the drawings:

Figure 1 is a side elevational view showing the switch about to be engaged by a moving part of a lathe.

Figure 2 is a top plan view of the structure shown in Figure 1.

Figure 3 is an irregular longitudinal sectional view through the switch.

Figure 4 is a horizontal sectional view taken substantially on the line 4—4 of Figure 3.

Figure 5 is a transverse sectional view taken substantially on the line 5—5 of Figure 3.

Figure 6 is a perspective view of the clamp plate.

Figure 7 is a perspective view of the adjustable contact head.

Referring to the drawings wherein like numerals designate like parts, it can be seen that numeral 5 denotes the bed of a lathe having a tapered guide rib 6 rising therefrom. Numeral 7 generally refers to a moving part of the lathe, which moves longitudinally of the bed 5 and serves to actuate the switch generally referred to by numeral 8 when it has advanced sufficiently toward the same.

The switch unit 8 is provided with a mounting which includes a clamp block 9 having a V-shaped longitudinal channel therein for accommodating the guide rib 6. This channel is located along one longitudinal edge portion of the block 9 while the other longitudinal edge portion, at the bottom side thereof is formed

with a narrow channel 10 for receiving the upper edge portion of the upturned flange 11 of an angle member 12, which is secured by screws 13 to the horizontal flange 14 of an angle member 15, this angle member 15 having a second flange disposed in the opposite direction from the intermediate portion thereof and this second flange is denoted by numeral 16, the same being secured by screws 17 to a box 18 which forms a housing for the switch mechanism.

An elongated tie bolt 19 extends downwardly through the block 9 and is screwed through the flanges of the angle members 12 and 15. Thus the angle members and clamp block 9 are clamped against the bottom and top sides of the bed 5, and by simply loosening the tie bolt 19, this mounting can be slid to any adjusted position on the bed 5 desired.

An elongated rod 20 is slidable longitudinally through the box 18, the same having a removable collar 21 at one end thereof beyond the box 18, while its opposite end is threaded as at 22 and threadedly disposed into a knurled contact head 23. A jam nut 24 on the threaded portion 22 prevents accidental unscrewing of the head 23. On the rod 20 is a block 25 of insulation which has a pin 26 extending downwardly therein to protrude into a longitudinal slot 27 in the rod 20. A stop member 28 is provided on the rod 20, while a coiled compression spring 29 is also provided on the rod and interposed between one end of the box 18 and the corresponding end of the block 25. Thus the block 25 is held against the stop 28.

An elongated contact strip 30 has one end portion secured to the bottom side of the block 25 by screws 31, 32, this end of the contact plate being struck to provide a depending lug 33 which acts as a stop for the block 25 by abutting a contact member 34 located upon a plate 35 of insulation. The other end of the contact strip 30 is offset downwardly as at 36 to wiping contact 37. The contact 37 is located on a plate 38 of insulation and as is shown in Figure 3, bushings 39 and 40 extend upwardly through the bottom of the box 18 to meet the plates 35 and 38, and binding posts 41 and 42 extend downwardly through the bushings 39 and 40 from the contacts 34 and 37. These binding posts are provided with nuts 43, 44.

One side of the box 18 is provided with a removable side plate 45 to permit access to the working details of the switch.

Obviously, the spring 29 will serve to maintain the rod 20 and block 25 to the right in Fig-

ure 3, with the current from a suitable source passing to the lathe power plant (not shown) by way of the binding post 41, contact 34, contact lug 33, strip 30, offset 36, contact 37 and binding post 42. When the moving part 1 of the lathe engages the adjustable head 23 and moves the head, the rod 20 will, in turn, move the block 25 to the left in Figure 3, disengaging the lug 33 from the contact 34, thus breaking the supply circuit, and if desired, a suitable signal lamp may be employed for indicating the disrupted circuit so that a machinist in a shop can tell from a distance that the lathe is not working, or has completed its job.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

5 A switch for mounting on the bed of a lathe and operation by a lathe part movable along said bed, said switch comprising a housing, an elongated rod extending horizontally through said housing and endwise movable therein from a normal position, a head on said rod adapted to be engaged by said movable part whereby said rod is moved in one direction, a block of insulation material fixed on said rod within said housing for movement with the rod, a pair of plate-like contacts on the bottom of the housing spaced apart lengthwise of the rod, an elongated bridging conductor of flat strip metal fixed to the bottom of said block and having an end 10 slidable over one of said plates and the other end thereof abutting one side of the other plate in the normal position of said rod, spring means 15 tensioning said rod against movement in said one direction, and means to mount said housing on said bed.
